UNITED STATES PATENT OFFICE.

GEORGE BRADFORD KELLY, OF JAMAICA PLAIN, MASSACHUSETTS, ASSIGNOR
TO THE AEOLIAN COMPANY, OF NEW YORK, N. Y., A CORPORATION OF
CONNECTICUT.

MUSIC-ROLL.

SPECIFICATION forming part of Letters Patent No. 718,256, dated January 13, 1903.

Application filed August 15, 1902. Serial No. 119,790. (No model.)

To all whom it may concern:

Be it known that I, GEORGE BRADFORD KELLY, a citizen of the United States, residing at Jamaica Plain, in the Commonwealth of Massachusetts, have invented certain new and useful Improvements in Music-Rolls, of which the following is a specification, accompanied by drawings.

My invention relates to music-rolls; and its object is to improve upon the means heretofore devised for locking the music-roll to the rotating parts in a mechanical musical instrument.

To this end my invention consists of a music-roll for carrying out the above object constructed substantially as hereinafter fully described and shown in this specification and accompanying drawings, in which—

Figure 1 is a side view of a rotary shaft of a mechanical musical instrument. Fig. 2 is a side view, partly in section, of a music-roll embodying my invention. Fig. 3 is an end view of the shaft, and Fig. 4 is an end view of the music-roll.

Referring to the drawings, the shaft A may be provided with any suitable means for rotating it, as the pulley B, while the music-roll C is adapted to be locked to the shaft and centered thereon in order that it may rotate with the shaft. A locking device is provided on one, adapted to coöperate with the other, as shown, in this instance the shaft A being provided with a pin D, adapted to a recess E in the end of the music-roll. Means are also provided for centering the roll on the shaft, one having a central recess in the end thereof and the other having a projection or reduced end, as shown in the drawings, the shaft A being provided with a reduced end F, adapted to a central recess G in the end of the roll.

In order to secure durability of the device, an annular plate H is secured at the end of the music-roll around the end of the recess

G and, as shown, embedded in the roll on 45 which plate the recess E is provided, to which the pin D is adapted.

It will be seen that by inserting the end F and pin D in the recesses in the music-roll the roll will be locked to rotate with the shaft. 50

Obviously my invention may be embodied in varying forms, and therefore without limiting myself to the construction shown and described nor enumerating equivalents,

I claim, and desire to obtain by Letters Patent, the following:

1. The combination of a music-roll and a shaft, one being provided with a recess and the other with a locking-pin adapted to said recess, the shaft having a reduced end adapted to a central recess in the end of the roll, whereby the shaft and roll may be locked to rotate together, substantially as set forth. 60

2. The combination of a music-roll provided with recesses in the end thereof, and a shaft 65 provided with a reduced end and a locking device, said reduced end and locking device being adapted to said recess in the music-roll, whereby the shaft and roll may be locked to rotate together, substantially as set forth. 70

3. The combination of a music-roll provided with a central recess in its end, an annular recessed plate embedded in the end of the roll about the mouth of said central recess, and a shaft having a reduced end adapted to the 75 central recess in the roll, said shaft being provided with a pin adapted to the recess in said annular plate, whereby the shaft and roll may be locked to rotate together, substantially as set forth. 80

In testimony whereof I have signed this specification in the presence of two subscribing witnesses.

GEORGE BRADFORD KELLY.
